SAFETY LOCK FOR RAILWAY SWITCHES

James W. McGarry, Cincinnati, Ohio

Application July 27, 1950, Serial No. 176,155

4 Claims. (Cl. 246—401)

1

The present invention relates to a safety lock for the movable switch point of a railway switch.

An object of the invention is to provide a switch point lock of simplified construction, which will securely lock the switch point and maintain it in locked position, notwithstanding the occurrence of accidents which may destroy or displace the switch stand and other parts of the equipment associated with the switch control.

Another object is to provide an improved switch point lock which may be manufactured at low cost, and which may be installed upon a rail tie with the expenditure of a minimum amount of time and skilled labor.

Another object of the invention is to facilitate and expedite manipulation of the switching equipment, without sacrificing safety and durability.

A further object is to incorporate into an effective switch point lock, features of construction which render the device properly operative under all types of adverse conditions encountered along the track-way, such as freezing weather and excessive dirt, grease, and other foreign substances to which the mechanism may be exposed.

The foregoing and other objects and advantages are attained by the means described herein and illustrated upon the accompanying drawing, in which:

Fig. 1 is an end view of a pair of rail ties supporting a conventional switch stand, and a safety lock constructed and applied in accordance with the present invention.

Fig. 2 is a cross-sectional view, on an enlarged scale, taken on line 2-2 of Fig. 1.

The switch stand 4 may be of any approved type, and may have as its principal elements a casing including legs 5 secured to the cross-ties; an upright rotary shaft 6 carrying targets 7 and 8, or possibly a lamp; and a weighted throwing lever 9 secured to a rock shaft 10 journaled in the casing. The rock shaft has connection with the usual gearing or linkage required for partially rotating the target shaft, and for reciprocating a connecting rod 12, which shifts the movable point of a switch. The throwing lever may be moved manually by the switchman, through approximately 180 degrees with shaft 10, to positions overlying one or the other of the cross-ties 13 and 14. All of the foregoing is common practice in the art, and requires no detailed explanation. It may be pointed out, however, that the usual connecting rod 12 which transmits motion of the switch stand mechanism to the switch point, reciprocates lengthwise of the ties in shifting the switch point to the open and closed positions.

The switch stand above described is commonly known as the ground lever type, or the parallel throw type.

5 The character 15 indicates a locking bar, which has one of its ends connected to the movable switch point, so that all movements of the switch point are transmitted to the locking bar. The
10 opposite end of said bar 15 extends in substantial parallelism with the connecting rod 12, to a location beneath and beyond the switch stand, where a perforation or stop 16 formed in or upon the bar may be engaged by a locking plunger 17, the purpose of which is to preclude longitudinal shifting of the locking bar under normal conditions.
15 When longitudinal shifting of the locking bar is to be permitted, incident to throwing the switch point, for example, the locking plunger 17 may be lifted or withdrawn from locking engagement with the stop or perforation of the bar 15, thereby relieving the bar of restraint so that the point of the switch may be moved by manipulating the throwing lever 9 of the switch stand.

The means for lifting or disengaging the locking plunger 17 from the stop or perforation 16 of the locking bar, may include a treadle 18 fixedly mounted upon a rock shaft 19 supported horizontally by the perforated upright arms 20-20 of a bearing bracket 21. One end 22 of the rock shaft may be turned substantially at right angles, 30 so as to extend as an arm alongside the rail tie, and the turned end of the rod may be reduced as at 23 to enter a flared transverse opening 24 in the head 25 of the locking plunger. This form of connection between the end of the rock shaft 35 arm 22 and the locking plunger, while preferred for reasons of effectiveness and simplicity, may be modified in various ways without substantially detracting from its general function.

40 From the foregoing it will be understood that by depressing the treadle or locking plunger actuator 18, preferably by means of the foot, the arm 22 will serve to lift the plunger 17 from the stop or perforation 16 of the locking bar, to release the bar for longitudinal reciprocation, and movement with the switch point. The locking plunger may be constantly urged downwardly toward the locking bar by gravity, assisted by a spring 26, if desired. A plug 27 confines the spring and forces it against the head of the locking plunger. The plug may be threaded into the bore 28 of the plunger housing, or be held in place by any other acceptable means. The head of the locking plunger has a sliding fit in the bore 28, of course.

55 At this point in the description, it may be noted

that the locking plunger housing is a metal casting or body providing an upright barrel 29 bored to accommodate the plunger head, the spring, and the plug or cap 27, the barrel being longitudinally slotted at 30 to permit elevating and lowering movements of the operating arm 22. Beneath the barrel is formed a transverse boss 31 cored or otherwise formed to provide a sleeve or bearing 32 loosely encircling and supporting the locking bar 15. The walls of the boss are counter-bored at 33—33 to support and guide the lower end of the locking plunger, the head of the plunger normally resting upon the flange or shoulder formed by the upper counterbore, as shown. This support for the head, though desirable, may be omitted if desired.

Integral with the barrel 29 and the hollow boss 31, are the mounting plate portions 34 and 35 of the casting or body, these plate portions being disposed at right angles to one another so that the plate portion 34 may rest against the vertical side of the rail tie, while the portion 35 rests upon the upper face of the tie, or within a recess 36 formed therein to permit the top of plate portion 35 to lie flush with the upper face of the tie. By means of bolts, screws or other fasteners 37, these plate portions of the casting or body may be securely fixed to the rail tie, as shown.

The apparatus of the invention includes, in addition to the switch point locking mechanism, cooperative means to restrain the throwing lever normally, and to release the throwing lever concurrently with retraction of the locking plunger, so that by the single act of depressing the treadle 18 with his foot, the switchman may with one hand throw the weighted lever 9 to actuate the switch stand and the switch point associated therewith. Such means includes a latch stand 39 having a base 40 to be secured by means of bolts, screws or the like, upon the upper face of the rail tie adjacent to the lock housing and its supporting plate 35. The stand 39 may be a casting or a stamping of metal, including a pair of spaced upright arms 41 and 42 between which may be loosely accommodated a latch trip lever 43, and a latch 44. The latch is pivoted at 45 between the arms 41—42 near the top thereof for free movement from the operative full line position, to the inoperative broken line position indicated at 46. These movements of the latch are controlled by the trip lever 43, which moves with the treadle 18.

The trip lever may be integral with the treadle if desired, or it may be a separate part secured to the rock shaft 19. In the example shown upon the drawing, the treadle has a hub 47 integral therewith, and the lever 43 is integral with the hub. A squared or angular hole in the hub fits over the correspondingly shaped end 48 of the rock shaft, to ensure against relative rotation of the parts. Accordingly, the treadle, the plunger operating arm 22, and the latch trip lever 43, always move in unison. Any of these parts may easily be replaced by removing the cotter pin 49, the washer 50, and the fasteners 51 that secure the bearing bracket 21 to the rail tie. The treadle and lever 43 may be secured to the rock shaft by means of pins, set screws, or otherwise if desired.

When the treadle is depressed, the upper end 52 of the trip lever bears against the adjacent edge of the latch and the cam 53 formed thereon, to rotate the latch in counter-clockwise direction about pivot 45, thereby to displace the nose 54 of the cam to a position between the spaced arms of the stand. With the nose of the latch

so displaced, the throwing lever 9 may be lifted and swung about the axis of the switch stand operating shaft 10. When returning the throwing lever to the home position illustrated, the latch will be struck thereby at the location X, resulting in momentary displacement of the latch to the inoperative position at which the throwing lever may enter the throat 55 of the lever rest 56. Upon seating of the lever upon the rest, the latch is returned to the operative position illustrated, by the action of its weighted end 57.

It will be understood from the foregoing explanation that latching of the throwing lever, when the lever is directed to its seat or rest 56, is automatic in the event that the switchman fails to depress the treadle 18. The weight 57 tends always to restore the latch 44 to operative position, and at the same time maintains the treadle in the normally elevated position, while maintaining the locking plunger in the locked position. However, the weighted end of the latch 44 cannot be depended upon entirely, to maintain the locking plunger 17 in locking engagement with the bar 15, for the reason that the latch trip lever 43 which normally may transmit the latch motions, is subject to breakage by accident. In fact, the latch trip lever 43 preferably is weakened by means of notches 59 or otherwise, to ensure breakage in the event that the latch stand and possibly also the switch stand, are swept from their positions upon the rail ties by objects projecting from a passing train. To ensure a locked condition of the locking bar 15 under such circumstances, therefore, the locking plunger is provided with a separate means, in the form of spring 26, to avoid the possibility of accidental switch point displacement due to destruction of any part or all of the equipment above the level of the rail ties.

The safety feature above mentioned may be enhanced and rendered effective to the maximum extent, by locating the treadle 18 and the locking plunger actuating elements beneath the level of the rail tie, as shown upon the drawing. The preferred method of accomplishing this, is to cut away the material of the tie from the upper face downwardly and outwardly to the tie end, thereby to form a lowered surface 60 upon which to mount the treadle bracket 21 and the rock shaft 19. This surface preferably is parallel to the upper face of the tie, and may be depressed a distance amounting to approximately half the thickness of the standard tie. The bracket 21 may be secured to the tie by means of the screws, bolts, or other fasteners 51, in proper relation to the latch stand and the locking plunger housing to ensure proper coordination of the working parts. With the arrangement as described and illustrated herein initial placement of the separate parts of the apparatus is made easy, and in the event of an accident resulting in destruction or displacement of any or all parts above the level of the ties, the locking function of the locking plunger will not be impaired, and the switch point will not be subject to displacement. Moreover, a quick repair can be effected by merely replacing the units damaged.

In the event that the throwing lever for the switch stand is to be protected against unauthorized manipulation, a padlock or other obstructive implement may be applied to the latch 44, at the perforation 61 which is located beneath a head extension 62 of the latch stand. When so locked, the latch cannot be rotated about its pivot

45 to afford access to the throwing lever. The switch point locking bar 15 is thereby protected against unauthorized manipulation also.

In conclusion, it is to be noted that the apparatus of the invention embodies various features which considerably advance the art, and promote safety in the operation of the railroad. Accidents resulting from derailments and collisions, due to the failure of switches to remain set after damage inflicted upon the switch stands, are reduced to a practical minimum by means of the invention herein disclosed. The absence of such derailments and collisions brings about a great saving in maintenance costs, and eliminates expensive loss of time which would otherwise occur by reason of traffic stoppage and extensive repairs to equipment. The device disclosed not only eliminates serious accidents, but at the same time makes possible a quick repair at low cost. The initial installation of this improved equipment, moreover, is performed at low cost without the aid of skilled labor or technically trained personnel.

Attention is directed to the simplicity of the parts and the method of assembly thereof, resulting in a durable apparatus easily kept in perfect operating condition. The operation of the device is unaffected by icing, or by heavy accumulations of dirt, grease, and other foreign substances. The various features mentioned are vital to safe and profitable railroad operations.

It is to be understood that various modifications and changes in the structural details of the device may be made, within the scope of the appended claims, without departing from the spirit of the invention.

What is claimed is:

1. Railway switch-point control apparatus for application to a rail tie having one end cut away downwardly and outwardly to the end of the tie, to provide a depressed open-sided flat seat as wide as the width of the tie, said apparatus comprising in combination: a switch-point locking bar connected to and movable with a switch-point, said bar disposed beneath the level of the upper face of the tie for reciprocation lengthwise of the tie, stop means on the bar remote from the switch-point, an upright movable locking element, a housing including guide means for the locking element and for the bar, the guide means having an interconnecting opening through which the locking element extends to engage the stop means on the bar, means for mounting the housing upon the tie at a location remote from the cut-away portion of the tie, a treadle bracket separate from the housing aforesaid, and means mounting the treadle bracket upon the tie within the cut-away area of the tie, a rock shaft extending transversely of the tie and journaled upon the treadle bracket for rocking movement upon an axis transversely of the tie and below the upper face of the tie, a treadle fixed transversely to the rock shaft, and an arm fixedly related to said shaft at approximate right angles, said arm having a free end loosely engaging the locking element, the treadle and the arm extending in opposite directions from the rock shaft lengthwise of and below the

upper face of the tie, with the arm disposed alongside of the tie, whereby downward depression of the treadle for movement in an upright plane extending generally lengthwise of the tie, serves to lift the free end of the arm and the locking element, to release the locking bar for movement with the switch-point.

2. The combination as recited in claim 1, including a latch stand for the throwing lever of a ground lever type switch stand, a movable latch on the stand to normally hold the throwing lever upon the stand, and an upstanding trip lever having a lower end fixed to the rock shaft, and an upper end in alignment with the movable latch, for displacing the latch and releasing the throwing lever with each depression of the treadle.

3. Railway switch-point control apparatus for application to a rail tie having one end cut away downwardly and outwardly to the end of the tie, to provide a depressed open-sided flat seat as wide as the width of the tie, said apparatus comprising in combination: a switch-point locking bar for connection to and movable with a switch-point, said bar disposed beneath the level of the upper face of the tie for reciprocation lengthwise of the tie, stop means on the bar remote from the switch-point, a movable locking element, a housing including guide means for the locking element and for the bar, the guide means having an interconnecting opening through which the locking element extends to engage the stop means on the bar, means for mounting the housing upon the tie at a location remote from the cut-away portion of the tie, a treadle separate from the housing extending outwardly toward the end of the rail tie, means movably mounting the treadle upon the tie over the depressed seat thereof, and below the level of the upper face of the tie, for movement in a vertical plane which extends generally lengthwise of the tie, and an arm actuated by the treadle, said arm lying alongside of the rail tie and having an end operative upon the locking element to move the locking element out of engagement with the locking bar upon depression of the treadle.

4. A railway switch-point control apparatus as specified in claim 3, including a stand to support a switch-point throw lever, an upright trip lever fixed relative to the treadle for movement therewith, and a shiftable latch on the stand normally restraining the throw lever, said latch being in the path of movement of the trip lever and displaceable by the latter, to free the throw lever with each depression of the treadle.
